TELEGRAPH SYSTEM

Gilbert S. Vernam, Hackensack, N. J., and Frederick G. Hallden, Bellerose, N. Y., assignors to Postal Telegraph-Cable Company (New York), New York, N. Y., a corporation of New York

Application March 22, 1935, Serial No. 12,364

20 Claims. (Cl. 178—2)

This invention relates to telegraph systems and more particularly to a polar simplex telegraph system, namely a system for transmitting polar telegraph signals in either direction over a line circuit, in one direction at a time, and without employing the usual duplex balance.

Such a polar simplex telegraph system may be used for manual signalling by means of the ordinary Morse code, but it is intended primarily for operating telegraph printers or teletypewriters of the start-stop type over line circuits whose transmission characteristics are such that they are not suitable for high speed operation by the ordinary neutral or "make and break" method of signalling, and where the polar half-duplex system cannot be used because of the excessive cost of the equipment required and the lack of trained repeater attendants for balancing the duplex terminal sets and repeaters.

One of the objects of the invention is to provide a system without duplex balance for transmitting polar signals under the control of a printer keyboard or tape transmitter at any one station on a line, and for receiving such signals on polar relays and causing them to actuate recording printers at any one or at all other stations on the line for the purpose of inter-communication.

Another object is to provide a telegraph system suitable for operation over long line circuits, having considerable resistance and capacity and which may be subject to interference from telegraph cross-fire or power line induction, without requiring reduction in sending speed or continual readjustments of relays or duplex balance to compensate for varying weather conditions.

Another object is to provide a system suitable for "way wire" circuits, having three or more stations in series with the line, without requiring costly and complicated repeaters at the intermediate stations.

Another object is to provide a system suitable for "way-wire" lines having a "main" station located in the central telegraph office at a relatively large city, where a supply of direct current is available, and having one or more "way" stations in smaller cities where only an alternating current supply is available.

A further object is to arrange the system so that the local direct current required at each way station is reduced to a minimum, so that it may be supplied by a small motor-generator or rectifier, and so that all local power may be switched off at the "way" stations when they are not actually in use for sending or receiving

messages. This results in considerable savings in the cost of power and power supply equipment and reduces the cost of maintaining the motor-generator or rectifier.

Still another object is to provide a simple and reliable method of selectively calling any "way" station by means of a code of bell signals, the bells being arranged to operate independently of, and to be unaffected by, the polar telegraph signals. The bell signals are also arranged to operate even though the printer motors are stopped and the local power supply is switched off.

Another object is to arrange the system so that the circuit can be linked at the main station to a duplex set or carrier channel terminal to extend the circuit for direct printer operation to any distance, without changing the method of polar simplex operation to the "way" stations.

Another object is to provide a "break" feature, to permit any operator to interrupt the sending station and obtain control of the circuit, which is positive in action, and, as compared with other systems, is less affected by line capacity and leakage. This "break" feature is also arranged to operate in the same manner when the circuit is extended over a polar duplex or carrier circuit.

Another object is to provide a system in which no preliminary operation of break keys or foot switches is required before sending, the operation of the printers and their keyboards being exactly the same as on an ordinary closed line circuit using neutral or half-duplex transmission.

Another object is to arrange the system so that line battery is always connected to the line at one station or at another, and in which line is not left grounded at both ends without battery supply, to avoid the need for biasing the polar line relays to prevent them from responding to ground currents or currents induced in the line from nearby circuits.

Another object is to provide a system having the features discussed above in which the equipment is relatively cheap, simple and reliable in operation, and in which any necessary operating adjustments can be readily made by untrained personnel.

An embodiment of the invention is illustrated in the accompanying drawings, wherein:

Fig. 1 shows the circuit of the main station, including the method of extending the circuit over a duplexed line; and

Fig. 2 shows the circuit of a "way" station and indicates how one or more additional "way" stations may be connected in series with the line.

To show the complete system, Fig. 1 should be placed to the right of Fig. 2. The line DL shown near the bottom of Fig. 1 extends to a half duplex set at a distant point and the leg or loop of this set connects to a start-stop printer. As the details of such sets and printers are well known, and as these details are not part of this invention, they have been omitted from Fig. 1.

In the drawings, certain of the relays are designated to indicate that they are polarized, slow-to-release, or slow-operating. As is well known, relays may be made slow-to-release or slow-to-operate by equipping them with copper slugs surrounding part of the core. The slow-operating relays have slugs at the armature end of the core, which make them slow-to-release as well as slow-to-operate.

Main station equipment

Referring to Fig. 1, the equipment at the main station MS consists essentially of a group of relays connected with the polar simplex line SL and associated with the printer set P and the duplex set D. The printer set P includes the keyboard contacts K, the printer line magnet LM and printer driving motor PM, which in this case may be a direct current motor with the usual centrifugal governor for maintaining its speed substantially constant. The printer set P is normally associated with the polar simplex set relays through the contacts of switching key SK, but if this key is operated, the printer is disconnected and the duplex set D is connected in its place for the purpose of extending the circuit over duplex line DL.

"Way" station equipment

Referring to Fig. 2, the "way" station WS has a group of relays, a printer set P' with its keyboard contacts K', line magnet LM' and motor PM'. This motor is preferably an alternating current motor either of the synchronous type or a series motor with governor. The necessary direct current for the relays is supplied by motor-generator MG. A rectifier with suitable filters may be substituted for this motor-generator, if desired.

One or more additional "way" stations may be connected in series with the line. One such station WS' is shown schematically, but its detailed circuit is not shown as it is the same as station WS. The outgoing line SL' is grounded after extending through the set at the last "way" station.

The circuits at both stations are shown in the idle condition. The power switch PS' at the way station is open, so that the printer motor PM' and the motor-generator MG are both shut off, and no local current is used at the "way" station. The power switch PS at the main station is in the "on call" position, the printer motor PM being shut off and the signal relay SR connected so that it can operate in response to an incoming call. The main station can also call any of the "way" stations, operating the single stroke bells, as SB, even though the local power is switched off at the "way" stations.

Polar simplex operation—general

In this polar simplex system, polar (+) and (-) signals sent from one station are received by polar relays connected in series with the line at other stations, and the circuit connections can be reversed automatically so that a station formerly receiving can send back to a station that was formerly transmitting. While sending polar

signals from one terminal station, the line is grounded at the other terminal station; and while sending polar signals from an intermediate station, the line is grounded at both terminal stations.

In the normal, idle condition, negative battery is connected to the line at the main station and the line is grounded at the terminal "way" station. When the main station sends, its pole changer PC transmits (+) spacing and (-) marking signals over the line, through the "way" stations in series, to ground. When a "way" station sends, its pole changers PCA and PCB connect the negative generator terminal to the line toward the main station and the positive terminal to the line toward the terminal "way" station and ground, to send spacing signals, and they reverse the generator terminals to send marking signals. The first spacing signal transmitted from any "way" station causes relay RS at the main station to disconnect the battery and connect the line to ground. Relay SS' at the "way" station also operates at this time to connect the marking contact M of the pole changer PCA to the generator. These relays, RS and SS', are arranged so that they remain energized as long as transmission continues from the "way" station, but they release shortly after transmission stops, thus automatically restoring the circuit to its normal idle condition, with negative battery connected to the line at the main station and with the generator effectively disconnected from the line at the "way" station. It should be noted that the direction of the marking and spacing current impulses in the line and through the polar line relays at each station is the same regardless of which station is sending.

Main station circuits—idle condition

Referring to Fig. 1 in the idle condition certain circuits are normally closed at the main station MS as follows:

1. A circuit from the grounded battery through keyboard contacts K, break key BK, contacts 1 and 2 of switching key SK and through the windings of the sending control relay SC and pole changer PC to ground, to hold these two relays energized.

2. From negative main line battery MLB through contacts 11 and 12 of receiving switching relay RS, marking contact and tongue of PC, upper windings of line relay L and break relay B, contacts 22 and 23 of calling relay C, line rheostat LR and over the line SL to the "way" station (Fig. 2), through the rectifier R and signal relay SR', calling key CK', contacts 51 and 52 of power relay PR and over outgoing line SL' and in a similar manner through any additional "way" stations as WS' to ground at the terminal "way" station. The current in this circuit holds the tongues of relays L and B against their marking contacts and holds the signal relay SR' at each "way" station energized. Because of the rectifier the current through the SR' relay is always in the same direction and the relay will remain energized as long as current in either direction flows over the line. The purpose of the rheostat LR is to adjust the line current to a normal operating value so the equipment will be adaptable for operating over lines of different lengths and resistances.

3. A circuit through holding rheostat HR and the lower or holding winding of relay B in a direction to hold the tongue against the marking

contact. This current is adjusted to about $1\frac{1}{2}$ times the strength of the line current.

4. From negative main line battery MLB through contacts 11 and 12 of relay RS , bias rheostat BR , contacts 26 and 25 of sending switching relay SS and through the lower or bias winding of relay L to ground. The bias rheostat BR is adjusted so that the current through the bias winding of relay L is slightly less than the normal current through the line winding. The difference in these two currents should be just sufficient to hold the relay tongue against its marking contact in spite of induced interfering currents in the line.

15 5. A circuit through the winding of break control relay BC and the marking contact and tongue of relay B , holding BC energized.

6. A circuit through the winding of holding relay H and contacts 18 and 17 of relay RS to hold relay H energized.

20 7. From grounded battery through printer line magnet LM , contacts 6 and 7 of switching key SK , marking contact and tongue of relay L and contacts 36 and 35 of relay BC to ground, holding magnet LM energized.

Calling the main station

To call the main station, the operator at any "way" station switches the local power on his set and operates the brake key BK' momentarily or depresses any key on the printer keyboard, which, as will be explained later, transmits — and + signals to the line. The first spacing signal reduces the line current to a low value, as negative potential applied to line SL from the "way" station generator opposes the negative main line battery applied to the line at the main station. If the line battery voltage at the main station is equal to the generator voltage at the "way" station and there is no leakage to ground from the line conductor, the line current will drop to zero, but if there is leakage or if the main station voltage is higher than that at the "way" station, the line current from the main station will be considerably reduced, but not to zero. In either case, the current in the lower or bias winding of relay L will overcome the line current through the upper winding and operate the relay tongue to the spacing contact. Relay G will operate over a circuit from negative main line battery through contacts 11 and 12 of RS , winding of relay G and resistance GR in parallel, contacts 21 and 20 of RS , spacing contact and tongue of L , and contacts 36 and 35 of BC to ground. Relay G closes an obvious circuit for operating the signal relay SR , which locks itself through its contacts 44 and 45 , lights the lamp signal LS and operates a vibrating call bell or buzzer VB . This bell or buzzer may be common to several main station sets similar to set MS , but connected to different line circuits. The bell indicates that a call is being received over one of these lines and the lamp signal shows which line. Relay RS will also be energized at this time, but its function will be described later.

To answer such a call, power switch PS is moved from the "on call" to the "operate" position, which starts the printer motor PM and releases relay SR , extinguishing the lamp and stopping the bell or buzzer. The main station set is now ready for receiving or sending messages.

Calling from main station

75 To call a "way" station, the calling key or

push button CK is depressed and released slowly several times to send the code call for the station desired. This operates relay C over an obvious circuit. Relay C opens the line SL , releasing the signal relay SR' at each "way" station and thereby tapping the single-stroke call bell SB at each "way" station. Relay C also connects a compensating resistance CR to relay B to maintain the continuity of the line circuit of the main station set and prevent the release of relay L while calling the way station.

It should be noted that an alternating current relay may be substituted for slow-release relay SR' and its rectifier R . The arrangement shown, however, has the advantage that it introduces less resistance into the line as a more sensitive relay, having a comparatively low resistance winding, may be used and the slow-release type relay used will hold up reliably during all printer signals.

Way station circuits—switching on and off

Local power at a "way" station may be switched on to answer a call from the main station, to call the main station, or to "listen in" on the line to determine whether it is busy before calling. In any case this is done by closing power switch PS' (see Fig. 2) which applies alternating current to the printer motor PM' and to the motor-generator MG . The motor-generator starts and supplies direct current to the following circuits:

1. From the positive generator terminal through the winding of holding relay HA , contacts 60 and 61 of holding relay HB to the negative generator terminal, energizing relay HA . The operation of the contacts 63 and 64 of relay HA breaks a short circuit around the winding of relay SC' extending by way of contacts 78 , 79 of SC' and 71 , 72 of SS' .

2. From the positive generator terminal through the windings of pole changer relays PCB and FCA and sending control relay SC' contacts 72 and 71 of sending switching relay SS' , break key BK' and keyboard contacts K' to the negative generator terminal, operating relays PCB , PCA and SC' . Relay SC' at its contacts 16 and 17 opens a short circuit including contacts 54 , 55 of PR around the winding of relay PR .

3. From the positive generator terminal through resistance RP , contacts 81 and 82 of power switch PS' , winding of power relay PR to the negative generator terminal. It should be noted that, as above stated, relay PR is normally short-circuited through its contacts 54 and 55 and contacts 71 and 76 of relay SC' , and that relay PR , therefore, cannot operate until after relay SC' and the pole changers PCA and PCB have operated. This prevents the pole changers from transmitting a spacing signal to the line while the set is being switched on and also prevents relay SS' from operating at this time (as contacts 55 and 56 cannot close until after contacts 76 and 77 open).

4. From the positive generator terminal through printer line magnet LM' , tongue and marking contact of line-break relay LB , break key BK' , and keyboard contacts K' to the negative generator terminal, operating line magnet LM' .

When relay PR operates, the line circuit is extended through both windings of relay LB in series, over a circuit extending from contacts 51 and 53 of PR through the upper winding of

LB, tongue and marking contact of PCA, lower winding of LB, contacts 75 and 74 of relay SS' and over the outgoing line SL' to ground. As the lower contacts of relay PR are of the make-before-break type, this action takes place without interrupting the line circuit or otherwise interfering with signals that other stations may be sending, except to cause a very slight reduction in line current due to the added resistance 5 of the windings of relay LB. If signals are passing over the line at this time, relay LB will respond to these signals and repeat them into the printer magnet LM' over circuit 4 described above. The printer P' will, therefore, record any 10 messages passing over the line.

If the printer indicates that the line is busy the power should be switched off by opening switch PS'. This will release power relay PR immediately and switch the incoming line circuit 20 directly through to the outgoing line. The other relays which were operated over the four circuits described above will remain operated for a brief interval while the voltage of the generator is dying down. It is obvious, therefore, 25 that the act of switching the power off at a "way" station will not interfere with signals passing over the line between other stations.

Transmission and reception at main station

30 Assuming that the power switch PS (Fig. 1) has been operated to start the printer motor PM, signals may be sent from the keyboard K to actuate relays SC and PC over a circuit previously traced. The first open or spacing impulse 35 from the keyboard will release these two relays and relay SC will close an obvious circuit for operating sending switching relay SS. Relay PC will transmit a spacing impulse from positive main line battery MLB to the line through the 40 upper windings of relays L and B. Relay B will not respond as it is held by current through its holding winding that is stronger than the normal line current (except that it may be momentarily operated by surges due to line capacity, the effect 45 of which will be described later). Relay L will respond to the outgoing signals, however, and the first time its armature touches its spacing contact, relay G will be operated over a circuit previously traced. In this case, signal relay 50 SR will not operate, as its circuit is open at switch PS. Relay RS will operate, however.

Relay SS will lock itself through its contacts 31 and 30 and through contacts 15 and 14 of RS to ground. With relays SS and RS both energized, negative main line battery is now connected to the marking contact of the pole changer PC through contacts 27, 26, 13 and 12. Rheostat BR is now short-circuited by contacts 13 and 12 of RS, and the lower or bias winding 60 of relay L is open at contact 25 of SS. The bias current is, therefore, removed from relay L and it will operate as an unbiased polar relay in response to the outgoing signals. Relay L in responding to the line signals opens and closes at 65 its marking contact the circuit of printer line magnet LM, so that the printer will make a "home record" of outgoing messages from the main station.

70 Relay H which was formerly connected to ground through contacts 18 and 17 of RS is now connected through contacts 19 and 20 to the spacing contact of line relay L. Relay H is of the slow-release type (it is also somewhat slow-to-operate, but this is not important). Relay H, 75 therefore, remains operated while its circuit is

being transferred to the spacing contact of relay L, and it remains operated as long as signals are being transmitted to actuate relay L. The condenser CX connected to relay H acts to prolong the impulses through the winding of relay 5 H by allowing the current to continue after the tongue of relay L leaves its spacing contact, while the condenser charges. Relay H remains operated, therefore, as long as relay L responds to printer signals, but it will release about one-half second after relay L stops with its tongue against its marking contact. Relay H provides a locking circuit for relay RS through the contacts of relay H and contacts 16 and 17 of relay RS, so that relay RS is no longer dependent 10 upon the contacts of relay G, which releases shortly after relay RS operates. It is obvious, therefore, that relays SS and RS will remain energized as long as signals are transmitted from the keyboard, but will release successively, (relay RS first and then relay SS) a short interval 15 after transmission stops.

When signals are transmitted from a "way" station, the first spacing impulse reduces the line current by opposing the negative main line battery, as previously described, thus allowing the bias winding of relay L to operate its tongue to the spacing contact. This grounds the line through relay G and its shunt resistance GR and operates relay G, as previously described. Relay 25 G operates relay RS, which transfers the circuit of relay H to the spacing contact of relay L in the same manner as for outgoing signals. Relay G releases, as its circuit is now open at contact 21 of RS but relay RS is held energized by relay 30 H, which remains operated as long as relay L is actuated by incoming signals. As relay RS is operated and relay SS is not operated, the line circuit SL now extends through the upper windings of relays B and L, tongue and marking contact of PC, contacts 12 and 13 of RS, contacts 26 35 and 25 of SS and lower winding of L to ground. It should be noted that the line relay now has no bias, as the negative battery circuit is open at contact 11 of RS and the rheostat BR is short-circuited by contacts 12 and 13. With both windings of relay L in series it will be more sensitive 40 to receive the polar signals from the distant "way" station. Relay L will repeat the incoming line signals through its marking contact M to printer 45 magnet LM, causing it to record the incoming messages. Relays H and RS will remain energized until transmission stops from the "way" station, after which they will release and restore 50 the main station circuit to its normal condition with negative battery connected to the line and the biasing circuit applied to the lower winding of relay L.

Transmission and reception at "way" station

60 Referring to Fig. 2, with the power switch PS' closed, relays PR, HA, SC', PCA, PCB, SR' and printer magnet LM' are normally energized as previously described. Relay LB is held energized by the line current from the main station so as 65 to hold its tongue against its marking contact. When signals are transmitted by the main station pole changer PC, as previously described, signal relay SR' remains energized but polar relay LB responds to the signals, repeating them into the 70 printer magnet LM' so that printer P' records the incoming messages.

75 When the "way" station keyboard K' is operated, the first open or spacing impulse releases relays PCA, PCB and SC' and the printer magnet 75

LM'. Relay PCA connects the negative generator terminal to line SL, through the upper winding of relay LB, while relay PCB connects the positive terminal of the generator over outgoing line SL' to ground, thus sending a negative impulse over the line SL to operate relay L at the main station, as previously described. Relay SC', upon releasing, closes a circuit from the negative generator terminal through its contacts 16 and 17, contacts 55 and 56 of PR, contacts 53 and 51 of HB and through the winding of sending switching relay SS' to the positive generator terminal, operating relay SS'. Contacts 73 and 75 of SS' connect the lower winding of relay LB to the positive generator terminal instead of to the outgoing line and ground. Contacts 12 and 70 of SS' connect the contacts of relay LB in series between the keyboard contacts K' and the winding of relay SC', so that the contacts of relay LB now control relays SC', PCA and PCB as well as the printer magnet. This change is for the purpose of controlling the "break", as will be described later.

Relay SS' establishes a locking circuit for itself through its contacts 68 and 69, through contacts 65 and 67 of relay HA and through the winding of relay HB to the negative generator terminal. As relay SC' is now released, a direct circuit for energizing relay SS' now exists through contacts 57 and 58 of HB, contacts 56 and 55 of PR and contacts 17 and 16 of SS' to the negative generator terminal, so that the winding of relay HB is now short-circuited and relay HB does not yet operate. Relay SC' operates, however, when the next closed or marking impulse is transmitted from keyboard contacts K', and relay SC' then opens, at its contacts 76 and 77, the short circuit around relay HB, so that relay HB now operates in series with relay SS', over the circuit previously traced through contacts 68, 69, 55 and 67.

The original operating circuit for relay SS' is now open at contact 51 of HB, and the circuit of relay HA instead of extending directly to the negative generator terminal through contacts 60 and 61 of relay HB, now extends through contacts 59 and 58 of relay HB, contacts 56 and 55 of PR to contact 71 of SC'. Relay HA, therefore, receives an impulse of current through contacts 77 and 76 of relay SC' every time a spacing impulse is transmitted from keyboard contacts K'. As relay HA is of the slow-release as well as slow-operate type, it will remain energized as long as signals are transmitted from the keyboard. Condenser CX' acts to prolong the impulses through relay HA, in the same manner as condenser CX at the main station. Relays SS', HA and HB, therefore, remain energized as long as signals are transmitted from the keyboard K'.

Relay LB is so connected that marking signals are transmitted through both windings in series, in a direction to hold its tongue against its marking contact. Spacing signals are transmitted to line only through the upper winding of LB, but, while spacing signals are being transmitted, the lower winding is connected across the generator over a circuit which may be traced from the positive generator terminal through contacts 73 and 75 of SS', lower winding of LB holding rheostat HR' and tongue and spacing contact of PCA to the negative generator terminal. The current in this circuit is regulated by rheostat HR' so as to be strong enough to hold the relay tongue against its marking contact in spite of the reversed current through its upper winding (except for surges due to line capacity, as de-

scribed later). It should be noted that, for outgoing signals, the printer magnet LM' is operated directly from the keyboard contacts K' to print a "home record" of outgoing messages, but for incoming messages it is controlled by the contacts of relay LB.

When transmission of signals from keyboard K' stops, relays SC', PCA and PCB come to rest energized, transmitting marking (+) potential to the line SL toward the main station. The circuit of relay HA is now open at contact 77 of relay SC'. After about one-half second, relay HA releases and opens the circuit of relay HB at contact 67, after first establishing a holding circuit for relay SS' through contacts 68, 69, 65 and 66, resistance RH, and contacts 62 and 61 of HB. After a further interval of about one-half second, relay HB releases, opening the locking circuit for relay SS' at contact 62, causing the release of relay SS' and re-operating relay HA through contacts 61 and 60. As two slow-release relays, HA and HB, must release in succession to release relay SS', while only one slow-release relay, H (Fig. 1), releases to de-energize relay RS, relay RS will always release before relay SS', if the relays are properly adjusted. Therefore, marking (-) battery will be applied to the line at the main station before marking (+) potential is removed from the line at the "way" station, and a double strength marking current will flow over the line momentarily whenever the "way" station stops sending. This serves no useful purpose, but it is important not to allow relay SS' to release before relay RS, as this would ground both ends of the line at the same time, reducing the line current to zero and possibly releasing relay L at the main station and the SR' relays at all "way" stations, tapping the signal bells.

If the "way" station operator, after sending part of a message, should hesitate long enough to allow relays HA, HB and SS' to release and should then start to send before relay HA had re-operated, relay SS' might operate at a time when its locking circuit is open. To prevent relay SS' from releasing, and thus interfering with the next marking impulse, a circuit is established from the negative generator terminal through keyboard contacts K', key BK', contacts 63 and 64 of HA and contacts 73 and 75 of SC' to relay PCA, thus short-circuiting relay SC' so that it cannot operate until after relay HA operates. The operating circuit for relay SS' through contacts 77 and 76 of relay SC' remains closed, therefore, until relay HA operates and establishes the locking circuit for relay SS' through contacts 65 and 67.

Breaking

To break or interrupt transmission from another station, it is only necessary to momentarily depress break key BK or BK', or to depress any key on the printer keyboard, several times in succession, using preferably a key which transmits more spacing than marking impulses such as the "blank" key or space bar. As soon as the spacing signals so transmitted coincide with spacing impulses from the other station, the double strength spacing current in the line will operate relays LB and B to their spacing contacts, overcoming the holding effect of the currents through rheostats HR and HR'.

Referring to Fig. 2, as relay SS' is operated while transmitting from the way station, relays SC', PCA and PCB as well as printer magnet

- LM' will be released, as their circuits are open at the contacts of relay LB. As long as the double strength spacing current exists in the line, the tongue of relay LB will remain against its spacing contact and spacing current will be transmitted from the "way" station pole changers PCA and PCB. Release of printer magnet LM' stops the printing and gives a definite indication of the break at the "way" station.
- 10 Referring to Fig. 1, relay B applies ground through its spacing contact and through contacts 29 and 28 of relay SS to the winding of pole changer PC, short-circuiting the pole changer and preventing it from re-operating. The spacing current from the main station continues, therefore, as long as relay SS remains operated. Break control relay BC releases after a short interval, as its operating circuit is now open at the marking contact of relay B. Relay BC applies an additional ground to the pole changer circuit and removes ground from the tongue of relay L, thereby opening the circuit of relay H which releases after a short interval and releases relay RS. Relay RS opens the locking circuit of relay SS at its contact 15, but signals from the keyboard K repeated through contacts 41 and 42 of relay SC will hold relay SS operated. The printer magnet circuit is held open at the marking contact of relay L to indicate the break to the main station operator.

When the main station operator stops sending on the keyboard, relay SC remains energized and, after a brief interval, relay SS releases, opening at its contacts 28 and 29 the short circuit around pole changer PC. Pole changer PC will operate and connect marking (—) battery to the line. The reduced line current will permit relays B and LB to close their marking contacts, operating relay BC at the main station and relays SC', PCA and PCB as well as the printer magnet LM' at the "way" station. If the "way" station operator has stopped sending, relays HA, HB and SS' will release and relay HA will re-operate, as previously described, restoring the circuit to its normal receiving condition. As the main station operator has also stopped sending, relay L will also operate, closing the main station printer magnet circuit. The main station circuit is now restored to normal and either station may transmit.

Calling from one "way" station to another

Although it is expected that the traffic handled will be chiefly between the main station and the "way" stations, there may be occasional messages to be transmitted from one "way" station to another. The calling key CK' has been provided to enable one "way" station to call another. This is done by operating the break key BK' and, while holding it operated, depressing and releasing the calling key CK' slowly several times to send the code call of the desired station.

Operating the break key releases relays SC', PCA and PCB and operates relay SS' as previously described, and transmits a spacing signal which causes relay L to operate relay G and relay RS at the main station, thus connecting the main station end of the line to ground. Operating calling key CK', while the break key is held depressed, releases relay SR' at each "way" station, and taps the bells in the same manner as when the main station calls. After calling, the break key is released to restore the circuit to its normal idle condition.

Transmission from one "way" station to another

As previously explained, the directions of current flow over the line for marking and spacing signals are the same regardless of whether the signals originate at a main station or at one of the "way" stations. It is obvious, therefore, that any "way" station can receive and record the messages sent from any other "way" station, if the local power is switched on.

When a "way" station operator operates the keyboard continuously and rapidly, the switching relay RS remains energized, and the line remains continuously grounded at the main station, with the main line battery disconnected. If the "way" station operator sends in a slow or hesitant manner, however, relay RS may release and apply negative battery to the line occasionally. This does not affect the proper operation of the printers at the main station or at the sending "way" station, as the bias current is re-applied to line relay L whenever relay RS releases, and the printer magnet LM' at the sending "way" station is operated directly over a local circuit by the signals from the keyboard contacts K'.

When negative battery is connected to the line at the main station, the next spacing signal from the sending "way" station reduces the line current substantially to zero, as previously explained, but does not reverse it. The line relay LB at another "way" station, which is receiving, would not respond to such an impulse unless it was adjusted to have a normal spacing bias, which is not desirable. Line relay L at the main station would respond immediately to such a spacing signal, however, and as soon as its tongue touches its spacing contact, it grounds the line through relay G and its non-inductive shunt GR, which are of comparatively low resistance. The line current reverses as soon as this ground is applied, and the receiving "way" station line relay there operates. The only noticeable effect of such hesitant sending, therefore, is to cause a slight delay or lag in some of the spacing "start" impulses, which causes a slight reduction in the range of orientation adjustment at the receiving "way" station printer.

Effects of line capacity

In the preceding description, the effect of line capacity was disregarded. Every line circuit will have a certain amount of electrostatic capacity to ground, and if the line includes a considerable amount of terminal cable, this capacity will have a noticeable effect on the action of certain relays.

When the polarity of battery connected to the line is changed, as by the release of relay PC, the polarity of the charge on the line conductor must be reversed. The current in the line increases rapidly to a peak value which may be several times the normal steady line current and then decreases to this normal current as the line becomes charged. This current surge is of brief duration and the line current usually decreases nearly to its normal steady value by the end of a single impulse in the printer code.

With equal line voltages at both stations and no line leakage, the "break current" will be twice the line current, but with leakage present the outgoing line current will be increased, the incoming current from the distant station will be decreased, and the break current will be less than twice the outgoing steady line current. In any case, the holding currents through rheostats HR and HR' must be less than the break current so that the break relays can operate as described.

The peak value of the current surge into the line at the beginning of a spacing impulse may exceed the break current, and either the break relays must be arranged so as not to operate on these surges, or else the circuit must be so arranged that if they do operate no bad effect on signal transmission will result. In certain other types of polar simplex systems the former method was used, the circuit being so arranged that part of the surge current was by-passed around the break relay. With this arrangement, however, the range of adjustment of the break relay is very small. The latter method has, therefore, been used in our system, i. e., the circuit is so arranged that the break relays may operate momentarily on line surges without affecting signal transmission.

Holding rheostat HR is adjusted so that the holding current through relay B will be less than the break current, but more than the normal or steady outgoing line current, and sufficiently strong so that the armature of relay B, if operated to its spacing contact by a line surge, will return to its marking contact before the end of a single spacing impulse in the printer code. As the armature of relay B is against its marking contact most of the time, slow-acting relay BC will remain operated. Relay B will ground the pole changer circuit momentarily during the first part of each spacing impulse, but, as relay PC is released at this time, no harm is done as long as relay B removes the ground before the next marking impulse starts. If the "way" station breaks, however, the armature of relay B will remain on its spacing contact preventing relay PC from sending marking impulses and relay BC will then release, as previously described. If the holding current is nearly as strong as the break current in the line, interfering currents in the line may cause the armature of relay B to chatter on its spacing contact during the break. This will have no effect, however, as the circuit controlled by this contact is also grounded by contacts 34 and 35 of relay BC. It is evident that this arrangement permits a wide range of adjustment of the holding rheostat HR.

The adjustment of rheostat HR' at the "way" station is similar to that of the rheostat HR at the main station. Relay LB may respond to spacing current surges without affecting signal transmission, provided its armature does not remain away from the marking contact long enough to prevent the sending pole changer's PCA and PCB from operating at the start of the next marking impulse. When the break current has operated relay LB, as previously described, it can chatter on its spacing contact without effect, as the spacing contact is not used in this circuit.

In addition to the effect of line capacity on the break relays described, surges may occur at the way station when keyboard transmission stops long enough to release relay SS'. Marking potential is connected to the line through both windings of relay LB before relay SS' releases and when it releases the potential is removed and the line is connected to ground. At this time, the line charge is dissipated by current surges in both directions, but principally through the windings of relay LB. This is equivalent to a short spacing impulse which is followed by the steady marking current from the main station battery, i. e., the line discharge surge may be strong enough to overcome momentarily the marking current in the line which is applied from the main station before relay SS' releases.

Relay LB may open its marking contact circuit momentarily as a result of such surges, but at this time its contacts are short-circuited through contacts 63 and 64 of relay HA and contacts 79 and 80 of relay SC'. Relay HA is slow-acting and does not operate until relay LB has closed its marking contact, so that such surges do not release the printer magnet.

Duplex set connections

It may be desired to extend the circuit from the main station to a distant city, so that the distant city may operate directly with one of the "way" stations on the polar simplex circuit. The line circuit to the distant city may be operated by carrier telegraph or by polar duplex, the method of connecting with the polar simplex set being the same in either case. As shown in Fig. 1 the sending and receiving legs of the duplex set are connected to the switching key 20 SK of the main office polar simplex set. This key should be operated. The distant end of the duplex line should terminate in a duplex set (not shown in the drawings) arranged for half-duplex operation with the loop connected to a 25 printer.

When the switching key SK is operated, the main station printer P is disconnected from the circuit, printer magnet LM being connected to ground through key contacts 4 and 5 to hold its 30 circuit closed. The marking contact of relay L is connected to the pole changer PC' of the duplex set through contacts 7 and 8 of the key, and sending relays SC and PC are connected to the contacts of line relay L' of the duplex set through contacts 2 and 3 of the switching key. The switching key SK also establishes at its contacts 9 and 10 a circuit from duplex pole changer PC' to contacts 33 and 40 of relays SS and SC, so that pole changer PC' will remain 40 energized whenever relay SC is released or relay SS operated, regardless of whether the tongue of line relay L is against its marking contact or not. This prevents pole changer PC' from responding to outgoing signals which are repeated by pole changer PC through the winding of relay L.

It is evident that any signals from the "way" station, which operate relay L, will be repeated by relay L over the sending leg to operate the pole changer PC' of the duplex set, which will transmit the signals to operate the printer at the distant city. Signals transmitted from the printer at the distant city will actuate the receiving relay L' of the duplex set which, in turn, 50 controls the sending relays SC and PC to repeat these signals over the polar simplex line in the same manner as though the signals originated in the main station printer keyboard. Relay SC releases on the first spacing impulse and 60 short-circuits the armature and marking contact of relay L, and then a more permanent short circuit is established by the contacts 32 and 33 of relay SS. This action prevents relay L from repeating back over the duplex line 65 the signals being transmitted to the "way" station, as these signals might otherwise interfere with the transmitted signals in the loop of the half duplex set at the distant city.

The operator at the distant city may break the 70 "way" station by opening his loop or operating his keyboard, and the "way" station operator may break by operating his keyboard or depressing his break key. In either case the action is the same as when breaking directly from the 75

main station printer, i. e., the "double strength" spacing current in the line operates the armature of relays B and LB to their spacing contacts and the pole changers at both stations are held released. When relay BC releases, it opens at its contacts 37 and 38, the sending leg of the duplex set and transmits a spacing signal to break the operator at the distant city.

What is claimed is:

10. A telegraph system comprising a main station and a way station connected by a line circuit, a transmitter and a receiver at each station, a source of current supply at the main station normally connected to the line during all idle periods, a source of current supply at the way station, means responsive to an initial operation of the transmitter at the way station for disconnecting the current supply at the main station and for connecting the current supply at 15 the way station to said line.
20. A telegraph system comprising a main station and a way station connected by a line circuit, a transmitter and a receiver at each station, a source of current supply at the main station normally connected to the line, a source of current supply at the way station, means responsive to an initial operation of the transmitter at the way station for disconnecting the current supply at the main station and for connecting the current supply at the way station to said line and responsive to the cessation of the operation of the way station transmitter to re-connect the main station source of current to the line and disconnect the way station 30 source from the line.
35. A telegraph system comprising two separated stations connected by a line circuit, a receiving relay at each station connected in the line circuit, a sending relay at each station having its tongue connected in the line circuit, a source of current at each station, the line circuit at one station being normally connected to the source of current thereat and normally grounded at the other station, a transmitter at said other station, means whereby the sending relay at said other station responds to the initial operation of the transmitter to connect the source of current thereat to said line thereby to transmit a spacing signal over the line circuit.
40. A telegraph system comprising two separated stations connected by a line circuit, a receiving relay at each station connected in the line circuit, a transmitting relay at each station having its tongue connected in the line circuit, a source of current at each station the source at one station being normally connected to the line circuit which is normally grounded through the marking contact of the sending relay at the other station, a transmitter at said other station, means whereby the sending relay at said other station responds to the initial operation of the transmitter to connect the source of current through the spacing contact of the relay to transmit a spacing signal over the line, and means rendered effective upon the response of the sending relay for disconnecting ground from the marking contact of the sending relay and connecting the source of current of said other station to said marking contact.
45. A telegraph system comprising a main station and a way station connected by a line circuit, a source of signalling current at the main station normally connected to the line circuit and the line circuit being normally grounded

at the way station, a source of current at the way station, a main station receiving relay having a winding connected in the line circuit and provided with a biasing winding, a source of biasing current connected to said biasing winding and poled to oppose the line current, a transmitter at the way station, said receiving relay being responsive to the initial operation of said transmitter, and means at the main station rendered effective by the response of said receiving relay to ground said line at the main station and disconnect the current source therefrom and also to remove current from said biasing winding.

5. A telegraph system comprising two separated stations connected by a line circuit, a receiving relay at each station connected in the line circuit and responsive to received message signals, a transmitting relay at each station having its tongue connected in the line circuit, a source of current at each station, the source 20 at one station being normally connected to the line circuit which is normally grounded at the other station, a transmitter at said other station, means whereby the sending relay at said other station responds to the initial operation of the transmitter to transmit a spacing signal over the line, and means rendered effective immediately upon the response of the receiving relay to said spacing signal to ground the line circuit at said station thereby effectively disconnecting 30 the source of current from the line circuit.

6. A telegraph system comprising a first station and a second station connected by a line circuit, a polar receiving relay at each station connected in the line circuit, a sending relay at each station having its tongue connected in the line circuit the tongue of the sending relay at the second station being normally grounded through the marking contact thereof, the spacing contact of the sending relay of the first station being grounded through a source of potential of one polarity and the marking contact being grounded through a source of potential of the opposite polarity while the tongue of said sending relay normally rests upon one of its contacts during non-signalling condition, and means for operating the first station sending relay to transmit polar signals over said line to the second station.

7. A telegraph system comprising a first station and a second station connected by a line circuit, a polar receiving relay at each station connected in the line circuit, a sending relay at each station having its tongue connected in the line circuit the tongue of the sending relay at the second station being normally grounded through the marking contact thereof, the spacing contact of the sending relay of the first station being grounded through a source of potential of one polarity and the marking contact being grounded through a source of potential of the opposite polarity while the tongue of said sending relay normally rests upon one of its contacts during non-signalling condition, means for operating the first station sending relay to transmit polar signals over said line to the second station, the spacing contact of the second station sending relay being grounded through a source of negative potential, means for operating said second station sending relay to transmit polar signals over said line to the first station, and means responsive to the initial operation of said second station sending relay to substitute at the second station a grounded source of positive potential for the 70 75

ground connected to the marking contact and to directly ground that contact of the first station sending relay which is normally grounded through a source of negative potential.

5 9. A polar simplex telegraph system comprising a main station and a way station connected by a line circuit, receiving and break relays connected in the line circuit at both stations, a sending relay at each station having its tongue connected in the line circuit, means including grounded sources of negative and positive potentials at each station, and connections therefrom to the marking and spacing contacts of the sending relays, whereby the spacing signals initiated at the respective stations are of opposite polarity while the marking signals at the respective stations are also of opposite polarity, the marking and spacing signals initiated at each station being of different polarity, and means for 10 causing the operation of the break relay at the main station upon increase of line current during the spacing interval.

15 10. In a polar simplex system, a combined polar receiving and break relay having two windings connected in series with the line circuit in combination with a sending relay having a tongue and marking and spacing contacts, means connecting said tongue and one of said contacts between the two windings of said relays and serving 20 normally to connect said windings in series, a resistance element connected across said normally closed contacts one winding of said relay being normally grounded and the spacing contact of the sending relay being normally connected to a source of negative potential, and means for 25 operating the sending relay to move its tongue from the marking to the spacing contact whereby a source of negative potential is connected through the spacing contact, said tongue and one 30 winding of said relay to the line while the other winding of the relay is connected in series with said resistance and thereby serves as a holding winding to prevent the operation of said relay on signal currents.

35 11. A polar simplex telegraph system comprising a main station and a way station connected by a line circuit, receiving and break relays connected in the line circuit at both stations, a sending relay at each station having its tongue connected in the line circuit, means including grounded sources of negative and positive potentials at each station and connections therefrom to the marking and spacing contacts of the sending relays whereby the spacing signals initiated at the respective stations are of opposite polarity while the marking signals at the respective stations are also of opposite polarity, the marking and spacing signals initiated at each station being of different polarity, means for 40 causing the operation of the break relay at the main station upon increase of line current during the spacing interval, and means for locking the way station sending relay to spacing position during 45 the continuance of the increased strength of the spacing break signal and for locking the main station sending relay to spacing position only so long as attempted transmission from the main station continues.

50 12. In a printing telegraph system, a line circuit, a relay in the line circuit for operating a telegraph printer to record message signals, a second relay traversed by message signals in the line circuit for operating a call signal, said second relay being independent of said printer and re-

5 sponsive to variations in line current but not responsive to message signals.

13. A telegraph system comprising a main station and a way station interconnected by a line circuit, a source of current associated with said circuit, means at said stations for sending telegraph signals over said circuit, rectifiers in said circuit at the way station, a slow-acting relay at the way station permanently fed with current through said rectifiers, means operable at will at 10 the main station for controlling the flow of current over said circuit and a call signal at the way station controlled by said slow-acting relay.

15 14. A telegraph system comprising a main station and a way station interconnected by a line circuit, a source of direct current at the main station connected with said line circuit and a source of alternating current at the way station, means at said stations for sending telegraphic messages over the circuit, relays permanently 20 connected with the circuit at said stations responsive to said messages, a slow-acting relay permanently connected with said circuit at the way station, a rectifier in the circuit on both sides of the connection of the slow-acting relay therewith, 25 a call signal at the way station controlled by said slow-acting relay, a calling key at the main station, a relay controlled thereby, follow-up contacts for the last-mentioned relay in said circuit, and a resistance connected with the tongue of the 30 last-mentioned relay.

35 15. A polar simplex telegraph system comprising two stations interconnected by a line, a duplex set at a station, means including a pole changer relay at said station for controlling the operation 40 of said duplex set, a line relay in said line at said station and having contacts for controlling said pole changer relay, means including a sending switching relay at said station for applying signalling currents of different potentials to said line, a 45 polar receiving relay forming part of said duplex set, a sending control relay controlled thereby and controlling said sending switching relay, a break relay at said station to interrupt transmission over said line, and a shunt around said contacts 50 of the line relay controlled by contacts of said sending switching, sending control and break relays.

55 16. A telegraph system comprising two stations interconnected by a line circuit, sending and receiving equipment at each station, a line relay at the first and a line break relay at the second station, each of said relays having two windings, means for connecting both windings of each relay in series during sending from the other station, 55 and means for energizing one winding for biasing and holding during certain other times.

60 17. A telegraph system comprising a main station and a plurality of way stations connected in series over a line circuit, transmitting and receiving equipment at each station, means including a power relay at a way station for operatively associating the way station with the line circuit, and means for maintaining the continuity of said line circuit at said way station in all operating 65 conditions of said power relay.

70 18. A telegraph system comprising a main station and a way station interconnected by a line circuit, sending and receiving equipment at said stations including an electromagnetic telegraph printer and a keyboard at the way station, a break relay at the way station for operatively associating the magnet of said printer with the line circuit when the way station is receiving messages, and a circuit independent of said relay 75

for operatively associating the printer magnet with the keyboard when the way station is transmitting.

19. A telegraph system according to claim 1
5 characterized by the provision at the main station of a slow-acting relay controlling the reconnection of the source of current to the line upon cessation of transmission from the way station, and the provision at the way station of successively operating slow-acting relays to prevent an
10 interval of no line current during the process of

restoration of the system to normal upon cessation of the way station sending.

20. A telegraph system according to claim 15 in which said shunt includes contacts of a break control relay controlled by the break relay, and 5 a slow-acting holding relay at said station controlled by said contacts of the line relay and contacts of said break control relay.

GILBERT S. VERNAM.

FREDERICK G. HALLDEN.
